UNITED STATES PATENT OFFICE.

ERNST METZNER, OF RACINE, WISCONSIN.

BRUSH.

1,172,544.

Specification of Letters Patent.

Patented Feb. 22, 1916.

Application filed March 8, 1915. Serial No. 12,720.

To all whom it may concern:

Be it known that I, ERNST METZNER, a subject of the Emperor of Austria-Hungary, residing at 1615 Sixteenth street in the city 5 of Racine, county of Racine, State of Wisconsin, have invented certain new and useful Improvements in Brushes, of which the following is a specification.

My invention relates to improvements in 10 brushes and particularly to hair brushes and other brushes employed for personal use.

The objects of my invention are to arrange the brushes in a series of separate longitudinal subdivisions and to provide a 15 hair parting tooth at the outer terminal of each subdivision.

These and various other objects I accomplish as set forth in the following specification and as more fully and particularly 20 pointed out in the appended claims, reference being had to the accompanying drawings in which several embodiments and adaptations of my invention are shown.

In the drawings, Figure 1 represents a 25 plan view of one form of my improved brush; Fig. 2 is an edge elevation of the brush shown in Fig. 1; Fig. 3 is a plan view of another form of my improved brush in which the bristles sections are made removable from the handle; Fig. 4 is an edge view of the form brush shown in Fig. 3; Fig. 5 is a transverse section through the brush taken on line 5—5, Fig. 3, to illustrate the dovetail interlock between the bristles sections 30 and the handle; Fig. 6 is a perspective detached view of the frame of one of the bristles sections; Fig. 7 is a plan view of another form of brush in which a solid unslotted back is provided and the bristles 35 sections are secured thereto on the under surface in parallel longitudinal separated arrangement; Fig. 8 is an edge view of the form of brush shown in Fig. 7; and Fig. 9 is an enlarged transverse section through 40 the brush shown in Fig. 8, taken on dotted line 9—9 in said Fig. 7.

In referring to the accompanying drawings in detail in which several forms, embodiments and adaptations of my invention 45 are illustrated, like numerals, letters, characters, and symbols designate corresponding and like parts.

In the form shown in Figs. 1 and 2, my improved brush has a back comprising 50 a terminal handle 1, a medial transverse solid portion 2, and a longitudinally-slotted

terminal portion extending from the portion 2 on the side opposite the handle and having a series of slots 3 which subdivide said portion and provide a plurality of longitudinal 60 extensions or tines 4 in parallel separated arrangement in which the bristles 5 are mounted and suitably secured in longitudinal subdivisions.

The outer extremity of each parallel extension or tine 4 is bent laterally and tapered to form a hair parting tooth 6, particularly as shown in Fig. 2 which is located at the outer end of the brush opposite the handle and serves to part the hair at the desired place coincidently with the brushing thereof.

In the form shown in Figs. 3, 4, 5, and 6, the brush back is constructed in a plurality of separate sections or parts, the handle 75 being in one piece and each extension or tine being in a separate piece which is detachably secured to the handle by fitting the end of said extension in a socket in said handle.

Referring to Fig. 3, the separate handle is represented by 7 and the transversely enlarged portion at the inner end thereof by 8.

A transverse row or series of grooves of dovetails 9 are formed in the under surface 85 of the portion 8, which are at equi-distances from each other and in parallel longitudinal arrangement. These grooves or dovetails extend to and through the inner end edge 90 of the portion 8, and terminate at their opposite ends at a short distance from where the handle begins as shown in dotted lines in Fig. 3.

The extensions of tines, or as I may term them, the bristle sections in this form of my improvement are constructed in two separate parts, an outer frame 10, and a base 11 in which one end of the bristles 12 are embodied and firmly and removably secured, said base being adapted to have sliding movement in the frame in assembling or dismounting the brush.

The frame is preferably formed of thin sheet metal or other suitable material and has a laterally-extending hair-parting tooth 13 at the outer extremity thereof, and a curved spring-locking strip 14 at the opposite or inner extremity.

It will be noted by referring to Figs. 3 and 4 that the base, when properly fitted in the frame, has a projecting portion 15, shown in dotted lines in said figures, which

is adapted to conform to and seat snugly in one of the grooves or dovetails 9.

To lock the bristles section to the handle, I preferably form a transversely-extending recess edged part 16 at the top of the transverse portion 8, which is of a curved form in cross section, as shown in Fig. 4, over which the curved strip 14 springs as the portion 15 is fitted in or withdrawn from the 10 dovetail.

The base 11 may be constructed of rubber or any other suitable material.

In the form of my invention shown in Figs. 7, 8, and 9, the back and handle are 15 constructed in one integral piece of metal or other suitable material, the handle which is represented by the numeral 7 in these figures, being of conventional form, and the back 18 being solid and unslotted except at 20 its outer extremity opposite the handle where a series of equi-distant short longitudinal recesses or slots 19 are formed to provide separated terminals 20 which are bent laterally at their outer extremities and tapered 25 constituting hair-parting teeth 21.

The under surface of the back is provided with laterally-extending longitudinal flanges 22 arranged in parallel pairs, and the bases 23 in which the bristles 24 are embedded are fitted between the members of the pairs of flanges 22, as shown in Fig. 9. The bases in this form of my invention or, in fact, in any form of the various forms thereof, may be constructed of rubber, wood, 35 celluloid, rubber or any other suitable and desirable material.

In my improved brush the handle is located at one end thereof, a transverse row of hair-parting teeth are arranged at the 40 opposite end, and a plurality of bristles sections are provided between the handle and teeth.

In parting and brushing the hair with my improved brush, the end teeth are utilized to separate and part the hair at the desired point, and the bristles or brush portion proper to smooth the hair, both operations taking place simultaneously, as the brush is moved relatively to the head.

50 While I have illustrated and described several forms of construction for carrying my invention into effect, these are capable of a wide range of variation, alteration, modification, and change without departing 55 from the spirit of my invention, I therefore do not wish to be limited to the construction herein shown and described but desire to avail myself of all such variations, alterations, modifications and changes as fairly 60 fall within the scope of the appended claims

or may be construed to be within the scope thereof by invoking the doctrine of equivalents.

What I claim as my invention and desire to secure by Letters-Patent is:

1. A brush comprising a body having an intermediate wide portion, a handle projecting from one end of said wide portion, and a series of hair parting teeth arranged in a transverse row at the opposite end of the 70 wide portion, and a plurality of bristles sections attached to the wide portion of the body, said bristles sections corresponding in number to the hair parting teeth and each section being in longitudinal alinement with one of said teeth.

2. A brush comprising a body having an intermediate wide portion, a handle projecting from one end of said wide portion, and a series of hair parting teeth arranged in a transverse row at the opposite end of the wide portion, a series of longitudinal flanges arranged in pairs on the under side of the wide portion of the body, suitable bases secured between the flanges of each 80 pair and bristles embedded in and projecting from said bases; said bases being equal in number to the hair parting teeth and each extending in longitudinal alinement with one of said teeth with the bristles projecting laterally therefrom in approximately the 85 same general direction as said teeth.

3. A brush comprising a back, a plurality of bases secured to said back in parallel separated longitudinal arrangement, bristles 95 embedded in and projecting from the bases, a handle extending from one end of the back and a series of hair parting teeth extending from the opposite end of the back in a transverse row, said teeth corresponding in number to the bases and each extending in longitudinal alinement with one of the bases.

4. A brush of the class described having a handle, a back provided with flanged parts and a series of independent bristles sections 105 each separately secured in one of said flanged parts and consisting of an outer frame, a base removably mounted in said frame bristles embedded in and projecting from said base, and a hair-parting tooth extending laterally from the outer extremity of the outer frame.

In testimony whereof I have hereunto affixed my name in the presence of two witnesses.

ERNST METZNER.
